N. C. WARD

COMPARTMENT BOTTLE

Filed Feb. 12, 1923

NEIL C. WARD.

By *Henry Ward* Atty

UNITED STATES PATENT OFFICE.

NEIL C. WARD, OF CHICAGO, ILLINOIS, ASSIGNOR, BY DIRECT AND MESNE ASSIGNMENTS, TO ORANGE CRUSH COMPANY, OF CHICAGO, ILLINOIS, A CORPORATION OF ILLINOIS.

COMPARTMENT BOTTLE.

Application filed February 12, 1923. Serial No. 618,523.

This invention has to do with containers and relates particularly to compartment bottles.

Primarily it is my object to provide a 5 multiple celled container in which several compartments may be simultaneously sealed. Secondarily it is my object to improvise means for carrying the several ingredients of a compound in cells separated one from 10 another but included within one larger or enclosing receptacle, and in which the isolation of such ingredients may be maintained until ready for admixture.

These and such other objects as may hereinafter appear are attained by the novel construction, combination and arrangement of parts to be hereinafter specifically described. Reference will now be had to the drawing forming a part of this specification 20 and in which:

Figures 1, 2 and 3 are vertical sections of embodiments of my invention.

Like reference characters are used to designate similar parts in the drawing and in 25 the description which follows:

Referring first to Figure 1, the ordinal 1 is used for designating a receptacle, which, in this case, is a wide mouthed bottle having a neck 2 and a flanged lip 3. Depending 30 within such receptacle 1, is a second receptacle, vessel or cell 4, here shown as being shaped somewhat like an inverted frustrated cone and of such diameter that its body may be readily inserted into neck 2 of bottle 1. Said inner receptacle 4 has at its larger and 35 open end an external radial flange 5 whereby it may be made to rest upon the lip 3 of bottle 1, and is kept from dropping thereinto.

40 A cap 6, which in this instance is the conventional bottle crown having a depending fluted rim and a compressible or cork lining, is provided for receptacle 1. The cap 6 when clamped upon the lip 3 of bottle 45 1 engages the flange 5 of the inner receptacle 4, against said lip to simultaneously seal the two receptacles, 1 and 4, from one another and against the discharge of their contents.

50 It is customary to construct the inner receptacle 4, of flexible material such as paraffin paper or rubber. But if it is desirable

to construct both receptacles of glass, a gasket or flat ring washer is placed intermediate said receptacles before crowning as 55 is shown in Figure 2.

When such inner receptacle 4^a is constructed of thin glass or other brittle or breakable material, a gasket 7 substantially "U" shaped in cross section and with the 60 open side inwardly disposed to receive the flange 5^a of said receptacle 4^a is provided. A cap 6^a is then clamped into position upon 3^a of neck 2^a of bottle 1^a, compressing the gasket 7, but not directly engaging the inner 65 receptacle 4^a.

Figure 3 shows a second modification of the structure of my device, such modification being arranged to accommodate the conventional cork or rubber stopper closure. In 70 this arrangement, a bottle 1^b having a constricted neck 2^b will receive therein an inner receptacle 4^b of substantially the same shape and diameter adjacent its top as said neck 2^b. A flange 5^b may be provided upon said 75 receptacle 4^b for limiting inward projection of said inner receptacle into bottle 1^b. A cork or stopper 6^b is forced home in the inner receptacle 4^b and so expands said receptacle that the latter frictionally engages 80 the walls of neck 2^b to seal the outer receptacle 1^b against loss of its contents.

It is apparent that the figures in the drawing do not disclose all of the embodiments of, or the changes, alterations, and modifications to which my invention may be subjected without departing from the spirit of my invention; hence, it is not my intention to be limited to the embodiments disclosed but to include all structures falling 85 within the scope of the appended claims.

What I claim as new and desire to procure by Letters Patent of the United States, is:—

1. In container construction, an outer member, an inner member having a flanged lip, a supporting element for said inner member and engaging said lip both from above and below, and a closure for the container sealing both members against loss 90 of contents.

2. A compartment bottle comprising a plurality of cells of different sizes, a closure member, and a gasket, said gasket being removably attached to a smaller cell and 100

providing means for seating said cell in a larger cell, and said closure member conjointly sealing both of said cells.

3. A compartment vessel comprising inner and outer cells, a closure member for the outer cell conjointly sealing said inner cell, and a gasket having one section intermediate

said cells and a second section intermediate said inner cell and said closure member.

4. A compartment vessel as described in claim 3, and in which said gasket is U shaped in cross section.

NEIL C. WARD.
